UNITED STATES PATENT OFFICE.

LUDGER E. LA BRIE, OF SOUTH BEND, INDIANA.

BRAKE SHOE.

Application filed June 3, 1926. Serial No. 113,367.

This invention relates to brakes and is illustrated as embodied in an internal expanding automobile brake having shoes of novel and improved construction. An object of the invention is to provide shoes pressed from sheet metal of such construction that metal of relatively light gauge may be used, while at the same time the shoe is so reinforced that it is of exceptional strength and 5 rigidity, thus providing a shoe which is both stronger and cheaper. It is also important that the shoe be formed in such a manner that its cylindrical face may be of extremely accurate curvature, thus minimizing the finishing operations on the shoe, this being especially important since it is not feasible to remove any considerable amount of material from the friction face when the metal is of very light gauge. At the same time the 10 light gauge metal is much easier to work, permitting the use of lighter and cheaper presses and facilitating the manufacture 15 generally.

Having these objects in view, the invention 20 contemplates the construction of the shoe in such a manner that the stamping includes a cylindrical flange terminating at one edge of the flange, this preferably being along one side of the friction face of the 25 shoe also, and continuing inwardly at the opposite edge (i. e. along the other side of the friction face) to form a stiffening portion which is shown as including an inwardly projecting stiffening web connected to the 30 cylindrical flange by a bracing portion. When this connecting or bracing portion is used, it may be pressed down at spaced intervals toward the inside of the cylindrical 35 flange to permit the ready insertion of rivets or other fastenings.

In all except the lightest shoes, I prefer to strengthen the above-described construction by means of a separate stamping or equivalent member having portions respectively 40 engaging the stiffening web and the cylindrical flange described above, and it is desirable that these portions of the reinforcing member be connected by an inclined portion diverging from the inclined portion of the 45 shoe body described above so that the shoe 50 includes a hollow or trussed body preferably generally triangular in cross-section, thus giving maximum rigidity. This inclined portion also may be pressed down at intervals 55 for the fastenings. When thus reinforced, the shoe may be regarded as built

up of two separately-formed stampings with cylindrical flanges secured together and providing the friction face of the shoe, and with inwardly-extending webs welded or riveted 60 together at their inner edges, the shoe preferably being hollow, and having (if desired) two series of depressed rivet seats.

Other features of the invention relate to a novel mounting of a thrust member to be 65 engaged by the cam or its equivalent, and to other novel and desirable particular constructions of the parts which will be apparent from the following description of the 70 brake shown in the accompanying drawings, in which:

Figure 1 is a vertical section through the 75 brake just inside the head of the brake drum showing the brake shoes in side elevation;

Figure 2 is an elevation of one of the end 80 shoes looking toward the cam end of the shoe;

Figure 3 is a partial section through the 85 cam end of the shoe on the line 3-3 of Figure 2 and showing the mounting of the cam so thrust plate;

Figure 4 is a section on the line 4-4 of 90 Figure 2 showing the integral bearings engaging the pivot for the shoe;

Figure 5 is a section on the line 5-5 of 95 Figure 2 showing the construction of the body of the shoe;

Figure 6 is a partial section on the line 6-6 of Figure 1 showing the overlapping 100 ends of two of the shoes;

Figure 7 is an elevation corresponding to Figure 2 but showing a modified shoe having a reinforcing member extending throughout its length;

Figure 8 is a side elevation of the shoe of 105 Figure 7;

Figure 9 is a section through the shoe of Figures 7 and 8 on the line 9-9 of Figure 8;

Figure 10 is a similar section on the line 110 10-10 of Figure 8;

Figure 11 is a section corresponding to Figure 9 but showing a third modification of the shoe;

Figure 12 is a section corresponding to Figure 9 but showing a fourth modification 115 of the shoe;

Figure 13 is a side elevation of the central shoe of the brake shown in Figure 1;

Figure 14 is an inside elevation of the central shoe shown in Figure 13;

Figure 15 is a section through the shoe of Figure 13 on the line 15-15 of Figure 13;

Figure 16 is a diagrammatic view showing one of the steps in manufacturing the shoe of Figure 5; and

Figure 17 is a diagrammatic side elevation looking in the direction of the arrows 17-17 in Figure 16.

The particular brake shown in Figure 1 includes a drum 10, at the open side of which there may be arranged a backing plate or other suitable support 12, and within which are arranged three brake shoes 14, 16, and 18, the shoes 14 and 18 preferably being identical and interchangeable. Shoe 16 is anchored by being mounted on a pivot 20 carried by the backing plate 12 while shoes 14 and 18 are connected to the shoe 16 by means of pivots 22 and 24, the details of the pivot 24 being shown in Figure 6.

The brake may be applied by suitable means such as a double cam 26 acting against the resistance of a return spring 28 connecting the shoes 14 and 18, the shoe 16 being applied by the shoes 14 and 18 (particularly the latter) against the resistance of an auxiliary return spring 30. Each of the shoes 14 and 18 is forked at its lower end to straddle one end of the shoe 16, the arms forming the forked end of the shoe being provided with relatively large openings 32 to provide ample clearance for the anchor 20.

The present invention relates to the construction of the shoes of a brake such as described above or any desired equivalent brake, preferably in such a manner that strong and rigid shoes may be constructed in an economical manner by pressing from sheet metal of relatively light gauge. Each of the end shoes 14 and 18, in the modification shown in Figure 1, comprises a pressed metal body including a cylindrical flange 40 providing the friction face supporting the brake lining 42, and terminating at one edge of the flange (at the lower side edge of the friction face of the shoe in Figure 5,) and integrally continued at the upper side edge of the friction face of the shoe in Figure 5 to form a connecting portion 44 extending toward the central plane of the shoe and projected between the sides of the shoe as a stiffening portion or web 46. An advantage of a construction of this sort is that the blank may initially be pressed out between two dies with connecting portion 44 inclined as appears in Figure 16, so that the portions 44 and 46 bottom in the die while the flange 40 is drawn out against the side of the die. This gives much greater accuracy in the curvature of the flange 40 than is possible when a cylindrical friction face is bottomed in the die. The stamping may be compressed to the form shown in Figure 5 by an additional operation illustrated diagrammatically in Figures 16 and 17, in which figures the support for the cylindrical flange 40 is shown at 48 and a support for the stiffening web 46

is shown at 50. While the flange 40 rests on the support 48 with the web 46 in engagement with the support 50, a die member 52 comes down on the connecting portion 44 and compresses it against the inside of the flange 40, thus forming the T-section shoe of Figure 5.

In order to form a fork at the pivoted end of the shoe, I attach a separate stamping 54 as shown in Figures 2 and 4, which is secured by rivets 55 or the like to the web 46 at its front end, and is then offset in one direction while the web 46 is offset in the opposite direction so that the separate part 54 and the web 46 project beyond the friction face of the shoe as a pair of spaced arms adapted to straddle shoe 16 and be mounted on one of the pivots 22 or 24. The web 46 and the part 54 may be provided with tubular bosses 56 forming bearings to be sleeved upon the pivots 22 and 24. At the opposite end a suitable cam thrust member 58 may be arranged in engagement with the end of web 46, the particular thrust member shown being fastened in place by means of a lug or other part 60 engaging or secured to the inner face of the flange 40 of the shoe and a lug or part 62 engaging and secured to one face of the web 46.

In the heavier brakes, that is, brakes of the larger diameters, I prefer to continue the part 54 as a reinforcing member 154 extending throughout the length of the shoe. When this is done I prefer that the portion 144 of the shoe body, corresponding generally to the portion 44 described above, should be an inclined portion connecting the flange 40 with a relatively short stiffening web 146, and depressed at intervals for the lining rivets or other fastenings 60 as appears in Figures 8 and 10. The part 154 may be provided with an inclined portion 62 connecting the portions which engage and are secured to the flanges 40 and the web 146, the two inclined portions 62 and 144 diverging from each other to form a hollow shoe body, preferably of triangular section. The inclined portion 62 may also be depressed at intervals as shown at Figure 10 for the lining rivets 60.

If preferred, in lieu of an inclined portion 62, a reinforcing member 254 may be provided as shown in Figure 11 having a flange engaging and secured to the inner face of the flange 40 and having a straight or radial web projecting approximately in the central plane of the shoe into engagement with the web 146. The construction in Figure 12 is substantially the same as that in Figure 9 except that in Figure 9 the web 146 has at its inner edge a short laterally turned stiffening part 64 which is omitted in Figure 12 and in Figure 12 the outer part of the reinforcing member 154 is spun over the free edge of the flange 40 to give a

finished rounded appearance to the edge of the shoe. Thus there is provided a strong, rigid, hollow shoe built up of stampings with cylindrical flanges secured together to provide the friction face, and with stiffening webs secured together in a joint running lengthwise of the shoe, and thus reinforcing each other.

As shown in Figures 13, 14, and 15, the central shoe preferably includes one part substantially as described above and including the flange 40 carrying the brake lining 42 and integrally connected to a stiffening web 46 by a connecting portion 44, except that the shoe is not forked at either end, the reinforcing member in this case being substantially the same as the above-described reinforcing member 254, illustrated in Figure 11.

While several illustrative shoe constructions have been described in detail, it is not my intention to limit the scope of the invention to those particular constructions or otherwise than by the terms of the appended claims.

I claim:

1. A brake shoe comprising a pressed metal part including a cylindrical flange forming at least part of the friction face and terminating at one edge of said flange and at the other edge integrally continued to form a stiffening web arranged between the edges of the shoe, said other edge forming one side edge of the friction face of the shoe.

2. A brake shoe comprising a pressed metal part including a cylindrical flange forming at least part of the friction face and terminating at one edge of said flange and at the other edge integrally continued to form a stiffening web arranged between the edges of the shoe, said other edge forming one side edge of the friction face of the shoe, together with a bracing portion connecting the flange and web.

3. A brake shoe comprising a pressed metal part including a cylindrical flange forming at least part of the friction face and terminating at one edge of said flange and at the other edge integrally continued to form a stiffening web arranged between the edges of the shoe, said other edge forming one side edge of the friction face of the shoe, together with an inclined bracing portion connecting the flange and web, the bracing portion being pressed down at intervals toward the inside of the cylindrical flange.

4. A brake shoe comprising a pressed metal part including a cylindrical flange forming at least part of the friction face and terminating at one edge of the flange and at the other edge of the friction face integrally continued from one side edge of the shoe as a stiffening web offset toward the central plane of the shoe and including a bracing portion connecting the flange and the inner part of

the web, in combination with a separately-formed pressed metal part including a cylindrical flange cooperating with the first cylindrical flange and an integral stiffening web between the side edges of the shoe and an inclined bracing portion connecting the flange and the web and diverging from the first bracing portion.

5. A brake shoe comprising a pressed metal part including a cylindrical flange forming at least part of the friction face and integrally continued along one side edge of the shoe as a stiffening web, in combination with a separately-formed pressed metal part including a cylindrical flange cooperating with the first cylindrical flange and an integral stiffening web secured to the first web.

6. A brake shoe comprising a pressed metal part including a cylindrical flange forming at least part of the friction face and integrally continued along one side edge of the shoe as a stiffening web arranged centrally of the shoe and an inclined bracing portion connecting the flange and web, in combination with a separately-formed pressed metal part including a cylindrical flange cooperating with the first cylindrical flange and an integral stiffening web arranged centrally of the shoe and an inclined bracing portion connecting the flange and web and diverging from the first bracing portion, the inclined portions being pressed down at intervals toward the cylindrical flanges.

7. A brake shoe comprising a pressed metal part including a cylindrical flange forming at least part of the friction face and integrally continued along one side edge of the shoe as a centrally-arranged stiffening web, in combination with a separately-formed pressed metal part including a cylindrical flange cooperating with the first cylindrical flange and an integral centrally-arranged stiffening web, one of said pressed metal parts being formed with an inclined bracing portion connecting its flange and its web.

8. A brake shoe comprising a pressed metal part including a cylindrical flange forming at least part of the friction face and integrally continued along one side edge of the shoe as a stiffening web, in combination with a separately-formed pressed metal part including a cylindrical flange cooperating with the first cylindrical flange and an integral stiffening web secured to the first web, one of said pressed metal parts being formed with an inclined bracing portion connecting its flange with its web, the inclined bracing portion being pressed down at intervals toward one of the cylindrical flanges.

9. A brake shoe including a pressed metal part having a cylindrical flange forming the entire friction face of the shoe and ter-

- minating at one side edge of the shoe, said part integrally continued at the other side edge of the shoe toward the central plane of the shoe and then projected inwardly to 65
6 form a stiffening web between the edges of the shoe.
10. A brake shoe including a pressed metal part having a cylindrical flange forming the entire friction face of the shoe and 70
10 terminating at one side edge of the shoe, said part integrally continued at the other side edge of the shoe toward the central plane of the shoe and then projected inwardly to form a stiffening web between the 75
15 edges of the shoe, in combination with a separately-formed reinforcing member engaging the inner face of the cylindrical flange adjacent its free edge and also engaging said stiffening web.
11. A brake shoe including a pressed metal part having a cylindrical flange forming the entire friction face of the shoe and terminating at one side edge of the shoe, said part integrally continued at the other 80
20 side edge of the shoe toward the central plane of the shoe, in combination with a separately-formed reinforcing member secured to said integrally-continued portion between the sides of the shoe and having 85
25 a cylindrical flange engaging and secured to the inner face of the first cylindrical flange at its free edge.
12. A brake shoe including a pressed metal part having a cylindrical flange forming the entire friction face of the shoe and terminating at one side edge of the shoe, said part integrally continued at the other side edge of the shoe as a stiffening web, in combination with a separately-formed reinforcing member secured to said web and to the cylindrical flange.
13. A brake shoe including a pressed metal part having a cylindrical flange forming the entire friction face of the shoe and terminating at one side edge of the shoe, said part integrally continued at the other side edge of the shoe as a stiffening web, in combination with a separately-formed reinforcing member secured to said web and to the inner face of the cylindrical flange and underlying a portion of the flange.
14. A brake shoe including a cylindrical friction part and a stiffening web, and comprising, in combination therewith, a thrust member engaging the end of the web and having a part engaging the inner face of the friction part and secured thereto.
15. A brake shoe including a cylindrical friction part and a stiffening web, and comprising, in combination therewith, a thrust member engaging the end of the web and having a part engaging the inner face of the friction part and secured thereto, and hav- 90
